HOLDER FOR COINS AND SIMILAR
ARTICLES

David V. Stroop, Glenbrook, Conn.

Application June 6, 1946, Serial No. 674,841

1 Claim. (Cl. 229—72)

1

My invention relates to holding devices for coins and for similar articles.

To the numismatist and to the philatelist it is a matter of consequence that coins, stamps, and the like be separately retained, convenient for viewing. In the case of certain articles of numismatic value it is particularly desirable that these articles be handled infrequently, preferably never. Previous holding devices have failed to meet or have only partially met these requirements.

It is, accordingly, an object of my invention to provide an improved means for retaining coins, stamps, and similar articles of value.

Another object is to provide a retainer which will permit the effective holding of small articles in full view for obverse and reverse inspection, and which at the same time will not expose these articles to handling.

A further object is to provide a holder of the character indicated having improved means for inserting and for removing small articles.

Other objects and various further features of novelty and invention will be specifically pointed out or will become apparent to those skilled in the art from a reading of the following specification in conjunction with the drawings, in which:

Fig. 1 is perspective view of a retainer according to the invention;

Fig. 2 is a partially broken-away plan view of a modified retainer; and

Fig. 3 is a partially broken-away plan view of an alternative arrangement.

Broadly speaking, my invention contemplates the use of a framing device having window openings, and coins, stamps, or other small articles are held in these windows by means of and between two layers of transparent material, formed as by a fold of a single piece of the material. In the forms to be specifically described, the frame bordering each window opening is open along preferably one side to permit the ready insertion and removal of these articles into and from the window space.

Referring to the embodiment illustrated in Fig. 1, one form of my improved retainer comprises a frame 5 having a plurality of coin-receiving window openings 6, 7, and 8. Frame 5 may be formed from two frame members 9, 10 punched with openings which, when in register, define the window openings 6, 7, and 8. Cardboard, or other similar stiffy pliable material, may be employed for the frame members 9, 10, and these members may be secured as by adhesive tape 11 along opposite outer edges of the frame 5 for a purpose which will later be clear. Additional securing

2

means which may include staples 12 are driven through the frame members 9 and 10 at points intermediate the window openings 6, 7, and 8 and near the outer frame edge not covered by the tape 11. Further staples 13 between and at the bottom of the windows may serve a purpose which will later be clear.

It will be clear that with the structure described I have provided a device having in effect a plurality of slots along the untaped edge of frame 5 (near the window openings) and that each of these slots is somewhat wider than the window opening which it accommodates. According to a feature of the invention, a simple holder of transparent material is receivable in any of these slots. In the form shown, this transparent holder comprises a single piece 14 of preferably pliable transparent material, such as cellophane, folded in half along the edge 15 to form an envelope or sandwich having two layers 16 and 17.

In practice a coin or other small article 18 is first placed between layers 16 and 17, and the folded edge 15 inserted into the slot accommodating one of the window openings 6. The transparent holder 14, being wider than the window opening 6, finds lateral support in the grooves alongside opening 6 as it is drawn further into the window opening 6. The stiffy pliable nature of frame members 9 and 10 permits the entrance of slot to bulge slightly as the coin 18 enters and as it passes through the slot; but once the coin is held within the window opening 6, it will be clear that this property of the frame members tends to resist outward displacement or loss of the coin through the slot. In the case of the window opening 7, a coin 19 is shown in its fully received and retained position, and in the case of window opening 8, a stamp 20 is similarly shown. The staples 13 will be seen to provide stops against which the coin holders may abut.

It will be clear that the described device, including its unique manner of supporting small articles of value, permits close detailed inspection of both obverse and reverse sides. If necessary, the articles may be easily removed separately; and, no matter how frequently inspected, they may be fully protected against soiling due to frequent handling.

In the modified arrangement of Fig. 2, I show a similar coin retainer in which the window openings permit the simultaneous introduction and holding of a plurality of items in each window opening. The arrangement is partially broken-away to show constructional features of this modified holder. Recalling the basic struc-

ture of the retainer of Fig. 1, the two frame members 9 and 10, and staples 12 and 13 will be recognized. However, instead of utilizing tape to bind outer edges of the frame members together, a layer of paper 21 or other similar material covers the top face of the retainer and is folded over opposite sides thereof as at 22 and 23 to perform the function of the tape. In the form shown, the frame members 9 and 10 are held together at the lower longitudinal side of the retainer by means of ribbons of paper 24 wrapped through a window opening, over, and around the lower edge of the retainer and back to the window opening, whereby the frame members 9 and 10 are securely held together both along the lower edge 25 of the retainer and along the lower window opening edges 26 as will be clear.

It will be appreciated that the device thus far described for Fig. 2 provides essentially the same features as that of Fig. 1, except that grooves are not available to receive the transparent coin holders 14 along the lower edge 26 of the window openings. Thus, the lower edge 26 serves as a stop against which the coin holders 14 abut when coins or other articles of value are inserted.

According to an alternative arrangement illustrated in Fig. 3, the transparent holder means is not removable from the frame member constituting the main body of the retainer; rather, a single folded piece of preferably pliable transparent material 27 extends longitudinally of the retainer to span at one time a plurality of window openings 28, 29, 30. Staples 31 may be employed to secure both frame members 9 and 10 and the transparent holder material together; at the same time, staples 31 serve to define the slots or pockets through which coins may be introduced into the various window openings. As in the case of the other forms which have been described, staples 31 are preferably driven at points spaced from side edges of the openings 28, 29, 30. To secure the lower, and in this form the unused, portion of the retainer of Fig. 3, staples 32 are driven into the frame members 9 and 10 near the lower corners thereof.

To permit the ready introduction of a coin 33 or other article of value into a window opening 28, the single piece of transparent material 27 is preferably folded along a line slightly displaced from its midsection. In this way, it will be clear that the outer edges 34—35 of the two coin-holding layers thereby formed will extend different distances. Preferably both of these edges are so formed as to extend slightly beyond the upper or coin-receiving edge of the retainer. It will be clear that the described arrangement of edges 34 and 35 of the transparent holding means permits ready location of the coin-receiving slots for any of the window openings 28, 29, and 30.

In the forms described, I have shown coin or stamp retainers having essentially the same outer dimensions but different arrangements of viewing and retaining windows. This consistency in

outer dimensions is preferred in some applications in which it may be desirable to file great numbers of retainers and in which these retainers are to be subjected to different uses—for example, in the display of related groups of coins or of unusually shaped articles. In any case, it will be understood that my invention is not limited to the specific configurations shown.

It is clear that I have provided an extremely simple means for the holding, storage, and protection of articles of numismatic and philatelic value. All the arrangements shown permit of ready obverse and reverse inspection, and the structures lend themselves to easy fabrication in quantities.

Although I have described my invention with particular reference to the forms shown, it will be understood that modifications may be made within the scope of the claims which follow.

20 I claim:

In a holder of the character indicated, a frame comprising two side sheets of stiffly pliable material in face to face relationship and having registering window openings therein, said sheets being secured together, adjacent edges of said side sheets at one side of said window openings being free of each other at the marginal edges of said side sheets to permit springing apart when an article to be housed is forced between the said marginal edges and into said window openings, and transparent sheet material covering each of said window openings at the inner side thereof to confine an article therein, the free edge of the transparent sheet material covering at least one of said openings being extended beyond the adjacent marginal edge of at least one of said side sheets to facilitate the insertion of an article between said transparent sheets and said side sheets, said two side sheets being spaced apart adjacent said window openings by the double thickness of said transparent sheet material only, an article housed as aforesaid being held against falling out between said marginal edges by those edges of the side sheets defining that side of a window opening adjacent said marginal edges, when said side sheets spring together after passage of an article between them and into a window.
